UNITED STATES PATENT OFFICE.

CHARLES E. PRATT, OF CHICAGO, ILLINOIS, ASSIGNOR TO THE INTERNATIONAL REGISTER COMPANY, OF SAME PLACE.

FARE-REGISTER.

SPECIFICATION forming part of Letters Patent No. 512,057, dated January 2, 1894.

Application filed January 5, 1893. Serial No. 457,364. (No model.)

To all whom it may concern:

Be it known that I, CHARLES E. PRATT, a citizen of the United States, residing at Chicago, in the county of Cook and State of Illinois, have invented a new and useful Improvement in Fare-Registers, of which the following is a specification.

My invention relates to fare registers such as are used for registering the fares of passengers on street cars and the like, and has for its objects to provide a simple, light, convenient, and secure register; also, to provide such a register with a sealed lock so that the register cannot be opened by any person without the breaking of the seal; also, to provide means for preventing access to the device.

My invention is illustrated in the accompanying drawings, wherein—

Figure 1 is a front view with parts broken away; Fig. 2, a rear view; Fig. 3, a horizontal vertical section taken from a point beneath the dials. Fig. 4 is a horizontal vertical section taken from a point beneath the tens dial and the direction indicator. Fig. 5 is a horizontal vertical section taken immediately back of the base plate looking from the back. Fig. 6 is a detail cross-section through the bell and locking mechanism. Fig. 7 is a cross-section on the line 7—7, of Fig. 4. Fig. 8 is a detail of the two parts of the case.

The same or like parts are indicated by the same letters in all the figures.

A is the front of the case, having the window A' through which the direction indicator is read, and the lower window A² through which the trip fares are read, and it is provided with the angular aperture A³ see Fig. 8 at one end, and two small apertures A⁴ at the other end Fig. 4, by the aid of which the front part of the case is secured to the rear, and with the aperture A⁵ through which the operating pull E⁶ projects, and the aperture A⁶ through which the end P⁹ of the dog P⁵, to control the direction indicator, projects.

B is the back of the case having the supporting links B' B' by which it is suspended, the screw holes B² B² whereby the base plate is secured to the back, the upper window B³ through which the total registration may be examined, the small window B⁴ through which

the ten thousands wheel J may be read, the seal window B⁵, and the keyhole B⁶.

B⁷ Figs. 3, 4, and 8 is a pin on the inside of the upwardly turned flange on the rear of the case B adapted to be received into the lateral portion of the angular aperture or slot A³ when the parts are properly brought to position.

The rear plate B has apertures similar to and registering with the apertures A⁴ in the front portion of the case A.

C is the base plate having at the lower end thereof the bell C' and the bell hammer C².

C³ is a pin having the depression C⁴ Fig. 6 to receive one end of the spring C⁵, which spring is secured at C⁶ on the base plate back of the bell. At the other end of the pin C³ is the bent portion C⁷ so that the two parts of the bend pass through the two apertures A⁴ A⁴ and the corresponding apertures in the back of the case when the parts are in position; and the pin B⁷ is in the lateral portion of the slot A³ forming a bayonet joint which aids in holding the two portions of the case together with the registering mechanism between them.

C⁸ is a pin on which the bell is supported. C⁹ Fig. 6 is an aperture through the base C of the case back of the spring C⁵, and C¹⁰ is a window of glass, or other such material to cover the aperture C⁹.

C¹¹ is a card back of such window bearing the name, seal, or stamp of the person in authority.

Referring to the trip registering mechanism D is the inner or units disk or dial, having the figures from 0 to 9, and D' is the tens dial having in like manner, the figures from 0 to 9. They are so positioned that the figured margin of each lies under the window A². The dial D is secured by means of the screw D² Fig. 7 on the front end of the shaft D³, the rear end of which is secured by a similar screw D⁴ led into a recess in the base plate C Fig.

7. Midway on this shaft D³ is secured the ratchet wheel D⁵ Fig. 4, toothed as indicated and provided at one point with the deep notch D⁶, and attached rigidly to the gear wheel D⁷, the cogs of which are cut away at one point, as D⁸. Journaled upon this shaft D³ is the

ratchet wheel D⁹ and the collar D¹⁰ and gear D¹¹, which are all riveted together, the gear D¹¹ having its teeth cut away at one side the same as the gear wheel D⁷. The dial D' is secured upon this last mentioned ratchet wheel D⁹ so as to rotate therewith.

D¹² and D¹³ are spring actuated dogs to lock the ratchet wheels D⁹ and D⁵ from reverse motion.

10 Pivoted upon the collar N encircling the shaft D⁸ is the lever E, which carries the dog E' Fig. 4, the same being pressed into the teeth of the ratchet wheel D⁹ by means of the spring E², and this lever E at its outer end is pivotally connected with the pull E³, which projects through the aperture A⁵, and is provided with the knob E⁴. The dog E' is cut away so that while its rear portion engages the inner ratchet at every action its outer portion only engages the front ratchet wheel when the rear portion of the dog has fallen into the deep notch D⁶ in the wheel D⁵, and by this means whenever the pull is drawn down, one or both of the trip dials operate, 25 and thus the fares of a given trip are indicated in units and tens by simply pulling on the knob. The permanent register consists of the dials J, the gear wheels G³, G⁶, G⁹, and G¹², the ratchet wheel G' and the plate F². Each 30 action of the lever E, however, causes the operation of the registering mechanism proper, for said lever is provided with gear teeth at F in which mesh the teeth F' on the plate F² which is pivoted on the shaft F³. This latter 35 plate F² is itself a lever and to its outer end is secured one end of the spiral spring F⁴, the other end of which is secured to the post F⁵. Thus the spiral spring F⁴ acts in opposition to the pull of the operator to return the pull E³ 40 and other parts to normal position.

On the rear side of the plate F² is the spring actuated dog G Fig. 5, which engages the ratchet wheel G' on the shaft F³, and from which projects the pin G² to engage the teeth of the pinion G⁸ on the shaft G⁴. This pinion has one long tooth G⁵ to engage the teeth of the pinion G⁶ on the shaft G⁷. The pinion G⁶ has a long tooth G⁸ to engage the pinion G⁹ on the shaft G¹⁰. The pinion G⁹ has a 50 long tooth G¹¹ to engage the pinion G¹² on the shaft G¹³.

G¹⁴ is a dog pivoted on the shaft G¹⁰ and adapted to lock the pinion G¹².

H H are spring actuated dogs to lock these 55 several pinions from reverse movement. On the end of these shafts F³, G⁴, G⁷, G¹⁰, and G¹³ upon which the pinions and the ratchet wheel are secured are placed disks J provided with numbers about their outer edges, and as the 60 lever F² moves back and forth with each operation of the lever E, the ratchet wheel G' moves one point and brings a new number into view through the window B³. When this ratchet wheel and shaft have moved once 65 around, the projecting finger G² will engage the next pinion G³ and move it one point so as to advance the disk controlled by said pin-

ion one number, and so on throughout the series, one being added each time to the total indicated by all the figures exposed to the window B³. The disk J on the last shaft G¹³ in the series is seen through the window B⁴, this being a convenience of arrangement to get the parts into the smallest possible compass. Thus as the trip registering mechanism operates, one unit is added each time to the permanent register or the total indicated thereby.

K is a pin on the back of the lever E adapted to engage the upwardly projecting pin K' on the base plate, the two serving as a stop to limit the motion of the pull E³; and L is a shield or guard plate alongside of the pull to prevent access to the operating mechanism through the aperture of the pull.

N is a collar surrounding the shaft D⁸ and serving as a pivot for the lever E, and provided with the oppositely faced ratchet teeth N' N² for the dog N³ pivoted on the lever E. This dog is provided with a back tip N⁴ to engage one extremity of the pivoted dog N⁵, which is pivoted on one end of the elbow crank lever N⁷, and whose other extremity engages the pin N⁸ on such elbow crank lever. The other end of the elbow crank lever N⁷ carries the bell hammer C², and this lever N⁷ is pivoted on the shaft N⁹ and is forced toward the bell by the spring N¹⁰. Thus by the same motion of the pull which operates the trip register and the permanent register, the dog N³ is moved, carrying with it the dog N⁵, and withdrawing the hammer C² from the bell until the motion is continued far enough to free the tip of the dog N⁵ from the tip N⁴ on the dog N³, whereupon the bell hammer is released and thrown against the bell to sound the alarm.

The dog N³ engaging the ratchet teeth N² will not permit of the discontinuance of the operation after it has once begun, for by this 110 dog, the pull is stopped from reverse motion after the end of the dog N³ has engaged the first tooth N². As soon as the bell hammer is released, the dog N⁵ is tipped upon its pivot so as to free it from the teeth N² and a new 115 operation can be performed.

The direction indicator and the releasing mechanism therefor consist of the following features:

O is a plate having the words "Out" and "In" or the like thereon, and it is secured to an arm O' pivoted to O² to a plate O³ which is secured on the shaft O⁴.

O⁵ is a pin at the extremity of the arm O'. The shaft O⁴ is secured rigidly upon the base plate C. On the shaft O⁴ is journaled the gear wheel P, having the eccentric groove P' in its surface to receive the pin O⁵, Fig. 3, and this gear wheel is cut away at P² P³ at diametrically opposite points. At the rear side of the gear wheel is the sleeve P⁴ having the rear part P⁴ with two notches one or the other of which notches receives one end of the dog P⁵ Fig. 5. The dog P⁵ is pivoted at P⁶, and

provided with a pin P^7 near the tip P^8 of the dog N^5 . The pin P^7 will pass the tip P^8 except when the dog N^5 is partially turned so as to withdraw the bell hammer from its position 5 near the bell, and in such cases, the tip P^8 engages the pin P^7 , and prevents the rocking of the dog P^5 on its pivot. P^9 is the outwardly projecting end of such dog which projects through the aperture A^6 . P^{11} is a guard 10 on such dog which substantially closes the hole through which it passes so as to prevent the introduction of a tool or wire into the interior.

R is a shaft inserted in a suitable bearing 15 R' , and this shaft carries an outer thumb piece R^2 and a pinion R^3 to engage the gear P . By means of this thumb piece, shaft, and pinion, the gear P provided with the eccentric groove can be rotated when the dog P^5 is 20 rocked inwardly so as to disengage its tip from the slot in the part P^4 .

It is evident that many of these features could be dispensed with without departing from the spirit of my invention, and also that 25 some of the features of the combination will operate successfully and satisfactorily if associated with other devices or forms of devices. I do not therefore wish to be limited to the precise forms of constructions shown, 30 or the details as shown, or to the entire combination.

The trip registering mechanism consists of the two dials numbered about their peripheries, and situated so that the numbered edge 35 or periphery of each will come back of the window A^2 . The inner dial D is the units dial, and it is controlled by the rear ratchet wheel D^5 . The outer dial D' is the tens dial, and it is controlled by the ratchet wheel D^9 . 40 The ratchet wheel D^5 has a deep notch D^6 , and by each pull of the pull E^3 , the ratchet wheel D^5 is moved forward one tooth by the engagement of the dog E' on the lever E therewith. This of course moves the units dial one point forward to indicate another 45 fare taken, and when the units dial has completed the revolution, the outer portion of the dog E' will engage the outer ratchet wheel, for the reason that the inner portion, which 50 has, up to that time, engaged the ordinary teeth of the ratchet wheel D^5 will sink deeper into the deep notch D^6 , thus permitting the outer portion of such dog to engage the tooth of the outer ratchet wheel. Thus by each pull 55 upon the knob or ball E^4 , the pull E^3 is brought downwardly and the lever E is moved about its pivot block N , and an additional fare is indicated on the trip register. The two ratchet wheels are kept from reverse motion by the 60 dogs D^{12} D^{13} .

One portion of the lever E is made the arc 65 of a circle, whose center is the center of the shaft D^3 about which center the lever E is pivoted. This arc shaped portion is indicated at F , and is toothed as shown. F' is a similar toothed lever pivoted on the shaft F^3 as shown in Fig. 5, and the radial distance from the

center of shaft F^3 to the teeth upon the lever F' is or should be the same as the radial distance from the center of the shaft D^3 to the teeth upon the lever E . These two toothed portions engage each other so that by every motion of the lever E , the lever F' is moved. This lever, whenever moved, by the engagement of the dog G with the ratchet wheel G' 75 moves the latter one tooth, and thus causes the numbered disk on the other end of shaft F^3 to move forward one number. The successive arrangements of gears, disks, and projecting points associated with the shafts G^4 , G^7 , 80 G^{10} , and G^{13} is designed to secure a permanent registration of all the fares; the first shaft F^3 and its mechanism and the dial J thereon indicating the units, the second tens, the third hundreds, the fourth thousands, and 85 the fifth tens of thousands, and these registrations are seen through the windows B^3 and B^4 . The dogs H H and G^{14} prevent the reverse motion of these several pinions. The pin K on the back of the lever E engages the 90 pin K' on the base plate to limit the motion of the pull E^3 . The lever E finds a stop in the opposite direction against the pin F^5 as shown in Figs. 3 and 4. The collar N on which the lever E is pivotally placed is itself fixed upon 95 the plate C , and has upon its surface the ratchet teeth N' and N^2 adapted to engage respectively the extremities of the dog N^3 which is pivoted on the lower side of the lever E . This dog has a back tip N^4 , and is itself adapted to receive one end of the dog N^5 , 100 so that as the lever E is moved about its pivot by the downward motion of the pull, the dog N^3 immediately engages the teeth N^2 so as to prevent the reverse motion of the parts and 105 compel the operator to complete the operation, the dog N^3 engaging the dog N^5 whose other end engages the pin N^8 , so that by the further motion of the lever E in the direction indicated by the arrow in Fig. 5, the dog N^3 is 110 rocked upon its pivot N^9 so as to retract the hammer C^2 from the bell. The reverse motion cannot take place until this motion has continued so far as to release the end of the dog N^5 from the tip N^4 , and when this occurs, the bell 115 hammer is released, and at the same time, the dog N^3 is freed from its ratchet teeth N^2 and the parts are restored to their original position. The dog N^3 will engage the ratchet teeth N' being forced there against by the 120 spring N^{11} , so that after releasing the bell hammer the parts must be freed so as to be restored to their original positions before a new operation of the pull can begin, and when this occurs, or when the pull has been 125 released so that the spring F^4 brings the lever E back against the post F^5 , the dog N^5 will resume the position shown in Fig. 5, back of the tip N^4 , so that as soon as the pull begins, if not before, the dog N^3 will be released from 130 the ratchet teeth N' and put in engagement with the ratchet teeth N^2 . Thus the operator when he begins to move the pull must complete the motion, and he must complete

it far enough to cause the bell to ring, and he must free the parts and let them resume their original positions before beginning the downward pull again.

- 5 Referring to the direction indicator; it consists primarily of the plate O having the words "In" and "Out" thereon, which are adapted to be successively exposed through the window A'. This direction indicator 10 plate is secured upon the arm or piece O' which carries the pin O⁵, which engages the eccentric groove P' in the gear P. The arm O' is pivoted at O² to the plate or arm O³ which is secured to the shaft O⁴. From this 15 it is clear that by the rotation of the gear P, the engagement of the pin O⁵ with the groove P' will bring such pin toward and from the center of shaft O⁴, and thus the indicator is moved up and down across the window A' so 20 that the words "Out" and "In" are successively exposed as stated above. This gear P is moved by means of the pinion R³ which engages with it, and which is fixed on the shaft R which is adapted to be received into 25 the vertical collar or hollow shaft R', and upon the outer end of which is the thumb piece R², by turning which the pinion R³ is turned, and hence the gear P rotated to cause the action last above described. On the inner end of the shaft O⁴ upon which the gear 30 P is journaled is the rearwardly projecting part P⁸ which is rigid or continuous with the gear P, and has at its inner end the plate P⁴ notched to receive one end of the dog P⁵. 35 This dog is pivoted at P⁶, and has a rearwardly projecting pin P⁷ to engage the tip P⁸ on the lever or dog N⁵. The pin P⁷ and tip P⁸ are in such relative positions that they may move past each other freely when the 40 dog N⁵ is in its normal position as indicated in Fig. 5. The outer end of the dog or lever P⁵ projects through the aperture A⁶ and terminates in the thumb piece P⁹ by pressing on which the dog may be rocked on its pivot. 45 The guard P¹¹ prevents access to the interior through the aperture A⁶. By pressing P⁹, the inner end of the dog P⁵ is freed from the disk P⁴, and then by rotating the thumb piece R² the direction indicator may be shifted. On 50 the opposite side of the disk P⁴ is a similar notch, so that when the direction indicator has been shifted, the parts are again locked. The gear P is adapted to engage the pinions D⁷ and D¹¹ so that when it is rotated, they also are rotated; and since the trip registering disks D, 55 D' are controlled by said pinions, they also are brought to zero with the shifting of the direction indicator. These pinions D⁷ and D¹¹ are cut away, as indicated at D⁸, so that when they 60 come around to the zero point, they are no longer engaged by the rotating gear P, and hence, when brought to zero cannot be further moved. The disk P⁴ is notched or slotted at diametrically opposite points so as to allow the dog P⁵ 65 to stop the rotation of the gear P when it has completed a half rotation, which is just enough to shift the direction indicator. The gear P

is itself cut away at the points P² P² at diametrically opposite points so as to clear the pinions D⁷ D¹¹. The arrangement of the pinions is such as indicated in Fig. 4, so that if an attempt be made to reverse the motion of the gear P to a direction opposite that of the arrow in Fig. 4, its teeth will engage the teeth of the pinions D⁷ and D¹¹, and thus it 75 will be locked from motion, the pinions D⁷ and D¹¹ acting as a dog to prevent the reverse motion, they being locked by the dogs D¹² and D¹². The relation of the pin P⁷ on the lever and dog P⁵ to the tip P⁸ of the lever or dog N⁵ 80 is such that as soon as the pull is drawn down far enough to cause the dog N⁵ to engage the second of the teeth N², the tip P⁸ is thrown around to such a position that the pin P⁷ engages therewith, and the shifting mechanism 85 can therefore not be operated until the operation of ringing is completed.

The key-hole B⁶ opens into an aperture S within the case, which itself opens into another aperture which contains the rotating 90 part S' having the teeth S² adapted to be engaged by the key. The part S' is pivoted to the back B. From this part projects the finger S⁴ which controls the slide S⁵ so that by operating the key, the slide may be moved 95 back and forth to conceal or reveal the permanent registration.

T is a chain depending from the curved portion of the pin C³, and carrying the bar T'. By this means the device when in position to 100 be used may be secured close to the person.

The use and operation of the seal lock of my invention are as follows: When the device is in position for use, the front and rear portions of the case are securely fastened together 105 by a bayonet joint at the top illustrated in Fig. 8, and by the engagement of the parts C³ and C⁷ with the set of registering holes in the two overlapping portions of the back and front parts of the case. In this position, the pin C⁵ is held from withdrawal by means of the spring C⁶ which lies in the cutaway portion C⁴. The only way therefore to open the case is to release these parts, and this can be done only by thrusting in a key or pin through 110 the aperture C⁹ against the spring C⁶ to release it from its engagement with the pin C³, whereupon the pin C³ with its parts C⁷ may be withdrawn, and the two parts of the case 115 may be separated. This, however, requires 120 the breaking of the glass C¹⁰, and the perforation or destruction of the seal card C¹¹, which bears the signature of the person in charge. While the case is thus closed, ready 125 for use, the guard L protects the aperture A⁵, to prevent the introduction of a wire along the pull E⁸, and thus to prevent interference with the mechanism. At the same time, the guard P¹¹ on the dog P⁵ in like manner protects the aperture A⁶.

I claim—

1. In a register, a direction indicator consisting of a rotatable part with an eccentric groove therein, an indicator pivoted at one

point and provided with a finger to extend into the eccentric groove at another point so that by the motion of the rotating part, the indicator is moved as the finger travels to or 5 from the center of rotation.

2. In a register, the combination of a gear with an eccentric groove in the flat side thereof, an arm secured on the shaft on which the gear rotates, an indicator pivoted at the extremity of such arm and provided with a finger which projects into the groove and means for rotating such gear.

3. In a register,—the combination of a gear with an eccentric groove in the flat side thereof, an arm secured on the shaft on which the gear rotates, an indicator pivoted at the extremity of such arm and provided with a finger which projects into the groove, and means for rotating such gear, and a locking dog to

prevent such rotation, but controlled from 20 without the register.

4. In a register, the combination of a gear with an eccentric groove in the flat side thereof, an arm secured on the shaft on which the gear rotates, an indicator pivoted at the extremity of such arm and provided with a finger which projects into the groove, and means for rotating such pinion, and a locking dog to 25 prevent such rotation, but controlled from without the register, and a bell hammer, and 30 interlocking portions on the hammer-lever and dog so that the gear cannot be released when the bell hammer has been moved away from the bell in the process of striking.

CHARLES E. PRATT.
